UNITED STATES PATENT OFFICE.

FRANK M. KINSMAN, OF CORTLAND, NEW YORK.

DIE FOR FORMING SHIFTING-RAILS.

SPECIFICATION forming part of Letters Patent No. 531,636, dated January 1, 1895.

Application filed March 6, 1893. Serial No. 464,663. (No model.)

To all whom it may concern:

Be it known that I, FRANK M. KINSMAN, of Cortland, in the county of Cortland, in the State of New York, have invented new and 5 useful Improvements in Dies for Forming Shifting-Rails, of which the following, taken in connection with the accompanying drawings, is a full, clear, and exact description.

This invention relates to improved dies for 10 producing shifting rails or similar articles of manufacture and with a minimum amount of stock.

Heretofore in making shifting rails or other articles of manufacture by means of drop 15 forgings, an unnecessary amount of stock has been consumed or wasted by being struck with a hammer and rendering it of such a condition as to be wholly valueless or else much time must otherwise be consumed in 20 preparing the stock so as to obviate this waste; and to the end of obviating all such difficulty my object is to produce a shifting rail and other articles of hardware, by first preparing the stock from which they are to 25 be swaged so that they may be forged in sets from a minimum amount of stock.

My invention consists in the new and novel dies hereinafter described and which are specifically set forth in the claim here- 30 unto annexed. They are constructed as fol- 70 lows, reference being had to the accompanying drawings, in which—

Figure 1, shows a piece of stock from which the articles are made. Fig. 2, shows various 35 dies used in the process. Fig. 3, is an end view thereof, showing the depressions in dotted lines. Fig. 4, is a top view of the stock after it has been swaged in the preparatory die. Fig. 5, is a top plan view thereof. Fig. 40 6, is a view thereof after it has been swaged in the second mold. Fig. 7, is an edge view thereof, showing the depression therein in dotted lines. Fig. 8, is a view of the stock after it has been swaged in the third and last

die. Fig. 9, is an edge view thereof. Fig. 45 10, is a view of the corner piece for the shifting rail, complete.

For the purpose of carrying out this invention, I first take a piece of stock, substantially as shown in Fig. 1, and swage it in a 50 die —a—, which gives it the form shown in Fig. 5. I then place it on the die —b— which has a raised portion —c— centrally of its central rectangular depression, for the purpose of throwing most of the stock into the 55 edges thereof. I then place it onto the die —d— where it is finally swaged into the form desired. The lower face of the successive hammers is used as a die, corresponding with the dies above referred to. 60

It will be observed that by having the raised portion centrally in the die —b—, I am enabled to force the stock to the edges thereof, so that when it is placed in the last die, the stock will be in the exact location 65 desired to form the L portion of the shifting rail. It will also be observed that but very little of the stock will be wasted; and that the articles can thus be made in pairs at a great saving of material. 70

What I claim as my invention, and desire to secure by Letters Patent, is—

The improved means for producing shifting rails, consisting of the die a, having a central rectangular depression, a die b, hav- 75 ing a central rectangular depression, with lateral extensions and a central raised portion central of its rectangular depression, and the die d, having approximately L-shaped depressions with extensions at opposite points 80 thereof, substantially as set forth.

In witness whereof I have hereunto set my hand this 17th day of January, 1893.

FRANK M. KINSMAN.

In presence of—

C. W. SMITH,
HOWARD P. DENISON.
